UNITED STATES PATENT OFFICE

110,083

DESIGN FOR A BILLIARD TABLE

Donald Deskey, New York, N. Y., assignor to The Brunswick-Balke-Collender Company, Chicago, Ill., a corporation of Delaware

Application February 23, 1938, Serial No. 75,351

Term of patent 7 years

To all whom it may concern:

Be it known that I, Donald Deskey, a citizen of the United States, residing in New York city, in the county of New York, State of New York, have invented a new, original, and ornamental Design for a Billiard Table, of which the following is a specification, reference being had to the accompanying drawing, forming a part thereof.

In the drawing:

The figure is a perspective view of a billiard table showing my new design.

I claim:

The ornamental design for a billiard table, as shown.

DONALD DESKEY.
